FIG. 2.

FIG. 3.

FIG. 4.

Inventor,
Henry M. Sheer
By Vernon E. Hodges, Atty.

UNITED STATES PATENT OFFICE.

HENRY M. SHEER, OF QUINCY, ILLINOIS.

HEATING SYSTEM FOR BROODERS, INCUBATORS, AND THE LIKE.

1,427,703.

Specification of Letters Patent. Patented Aug. 29, 1922.

Application filed May 7, 1921. Serial No. 467,722.

To all whom it may concern:

Be it known that I, HENRY M. SHEER, a resident of Quincy, in the county of Adams and State of Illinois, a citizen of the United States, have invented certain new and useful Improvements in Heating Systems for Brooders, Incubators, and the like, of which the following is a specification.

This invention relates to heating systems for brooders, incubators, and the like.

The primary object of the invention is to maintain a constant, uniform and unobstructed flow of oil to the burner.

The further object is to so construct the automatic control that it will effect a higher or lower oil level according to the temperature of the oil.

A further object is to arrange an oil feeding device adjacent the burner, whereby the carbon forming at the entrance of the oil to the burner may be broken up, and the oil feeding duct kept clean.

In the accompanying drawings:

Fig. 1 is an elevation partly in section disclosing my heating system complete;

Fig. 2 is a bottom plan view of the float;

Fig. 3 is a top plan view of the burner base and support.

Figure 4 is a top plan view partially in section, of a burner and oil chamber with connection there-between.

Fig. 5 is a detail view of the valve mechanism of the oil chamber, and

Fig. 6 is a vertical section on the line 6—6 of Fig. 1.

The numeral A indicates the main tank; B, the auxiliary supply tank or reservoir; C, the burner support; and D, the burner base.

The auxiliary supply tank B preferably consists of a cylindrical receptacle divided into upper and lower compartments 1 and 2, being divided by a transverse disk 3. The upper end of the compartment 1 is open and adapted to receive the main supply tank A, while at the bottom thereof is arranged a screen or netting spaced therefrom and supported upon a cylindrical flanged member 5. Immediately above the screen 4 is placed a filtering medium 6, preferably consisting of a heavy cloth, over which is placed a quantity of cotton batting or other similar material 7.

The partition 3 is provided centrally thereof with a downwardly projecting nipple 8, having a small central opening 9

terminating at the lower end thereof in a valve-seat 10. The numeral 11 indicates a float constructed of cork or other suitable material, located in the lower compartment 2. In the central opening 12 of the float is arranged a valve-stem 13 secured to a thermostat consisting of spaced members 14 and 15, the lower member 15 being provided with a threaded stem 16 adapted to be secured to a disk 17, the latter being secured to the lower side of the float 11 and provided with a plurality of openings 18 adapted to permit the oil to seek its level in the central opening 12.

The upper end of the valve-stem 13 is countersunk and adapted to receive a high-grade perfect steel ball 19, the ball adapted to seat itself about two-thirds of its diameter in the valve-stem 13. By this construction, when the fuel has risen a sufficient height in the lower compartment, the ball-valve will act to cut off the supply from the upper compartment.

The purpose of the thermostatic arrangement is to effect a difference in the relative height of the ball-valve and the float according to the temperature of the oil. The contraction of the metal disks 14 and 15 (when the oil is cold) causes the float to rise relative to the ball-valve, thereby effecting a slightly higher level in the lower chamber, whereby, when the oil is warm, the expansion of the metal disks 14 and 15 causes the ball-valve to rise relative to the float, producing a slightly lower oil level in the lower chamber. This is desirable to compensate for the slowness of the flow of oil when cold.

The auxiliary reservoir B is preferably supported upon a base 20 provided with a hollow threaded portion 21 adapted to receive the hollow threaded stem 22 secured to the bottom of the reservoir 1 by reinforcing member 23.

The numeral 24 indicates a threaded disk or lock-nut received upon the hollow threaded stem 22, the former being countersunk on the underside and adapted to receive a leather washer 25 which is provided with internal screw-threads, thereby effecting a tight fit between the stem and the locking nut 24.

Leading from the base 17 is a feed-pipe 26, to the outer end of which is connected a burner support consisting of a hollow upright portion 27 somewhat enlarged at the

upper end thereof, forming an oil chamber 28, which is preferably provided with a removable cap 29.

Received within the bore of the upright portion 27 is a plug 30, the upper end of which is reduced in diameter and provided with lateral ports 30'. Arranged below the lateral ports is a valve seat 31, and received in the upper end of the plug is a valve-stem 32 adapted to seat upon the valve-seat 31. As indicated, this valve-stem 32 extends upwardly through the removable cap 29, and is bent at right-angles forming a handle 33. It is obvious, however, that the valve may be 15 of such a construction as to be entirely concealed within the oil chamber by the removable cap 29.

The numeral 34 indicates a burner base provided with an annular groove 35. Extending horizontally from the oil chamber 28 is a hollow tube 36, which communicates with an oil-well 37 arranged beneath and in communication with the annular oil groove 35. Arranged in the hollow tube 36 is a squared 25 rod 38 adapted to reduce the opening in the inside of the hollow tube 36, and provided with a plurality of ports 36' serving to vent the upper side of the pipe as well as provide a channel for the oil on the lower side.

30 The rod is of sufficient length to extend into the oil-well 37 at one end, and within the oil-chamber 28 at the opposite end, being provided at this end with a transverse opening 39, whereby when the cap 29 is removed, the squared rod 38 may be oscillated or shifted to distribute any sediment or sluggish oil which may accumulate.

If desired, the burner may be entirely removed for cleaning, it being merely necessary 40 to close the valve 32, thereby eliminating the necessity of changing the oil control adjustment at the reservoir.

Another advantage of having a valve below the oil chamber in the burner support 45 is that it enables one to fill the annular oil groove of the burner, together with the oil chamber, with gasoline or the like, for starting, and prevents the charge from finding its way into the oil feed pipe, thereby reducing the amount of gasoline necessary to 50 start.

In operation, the reservoir is adjusted to such a height with respect to the supporting base as to bring the oil in the compartment 55 containing the float on a level with the opening in the hollow tube 36 adjacent the burner, at which level the ball-valve is seated upon the valve-seat 10, cutting off the flow of oil to the lower compartment.

60 To vary the height of the oil in the float compartment and the oil chamber 28, it is only necessary to adjust the height of the reservoir 1 with respect to the base 17. To reduce the oil level in the float chamber, a lock-nut 24 is unscrewed, and the container

or reservoir 1 is screwed down or turned to the right, while raising or turning to the left will increase the height of the oil in the float chamber and correspondingly increase the flow of oil to the burner, or rather 70 it increases the height of the oil in chamber 28. When the proper height is determined, lock-nut 24 is screwed down holding the container 1 in the adjusted position. The thermostatic arrangement on the float 75 proper is to effect an additional oil regulation between the burner and the compartment B, which is determined by the temperature of the oil, the thermostat proper expanding and contracting accordingly. This 80 is desirable to compensate for the slowness of the flow of the liquid when the oil is cold.

I claim:

1. A heater comprising a burner adapted 85 to burn a liquid fuel, a reservoir consisting of upper and lower compartments, a hollow nipple extending from the upper compartment to the lower compartment, a float arranged in the lower compartment, and a 90 thermostatically controlled valve carried by said float adapted to close the opening in the nipple, when the oil has reached a predetermined level.

2. A heater comprising a burner adapted 95 to burn a liquid fuel, a reservoir consisting of upper and lower compartments, a hollow nipple extending from the upper compartment to the lower compartment, a float arranged in the lower compartment, a thermostatically controlled valve carried by said float adapted to close the opening in the nipple, when the oil has reached a predetermined level, and means for regulating 100 the height of the reservoir for changing the level of the oil in the lower compartment.

3. A heater comprising a burner adapted 110 to burn a liquid fuel, a reservoir consisting of upper and lower compartments, a float arranged in the lower compartment, a thermostatically controlled valve carried by said float for regulating the height of the fuel therein, a base for supporting said reservoir, and means for regulating the reservoir relative to the base for determining the height of the oil in the lower reservoir.

4. A heater comprising a burner adapted 120 to burn a liquid fuel, a reservoir, a disc therein dividing the reservoir into two compartments, a hollow nipple mounted on the disc extending into the valve compartment, a float arranged in said last mentioned compartment and a thermostatically controlled valve carried by said float and adapted to 125 close the opening in the nipple when the oil has reached a predetermined level.

5. A heater comprising a base, a reservoir consisting of upper and lower compartments arranged above said base, a burner, an oil- 130

- chamber adjacent to, and in communication with said burner, a feed-pipe connecting the lower compartment of the reservoir to the oil chamber adjacent the burner, a float arranged in the lower compartment reservoir for maintaining a perfect oil feed in said lower compartment from said oil chamber and thermostatic means carried by said float for varying the control action of said float
- 5 according to the temperature of the oil, and means for regulating the height of the reservoir relative to the base for changing the level of the oil in the lower compartment of the reservoir and the oil chamber adjacent the burner.
- 10 6. A heater comprising a burner adapted to burn a liquid fuel, a reservoir for the liquid, an automatic control, means interposed between the burner and the reservoir for regulating the supply of fuel to the burner, means interposed between the burner and the control device for restricting the flow of fuel to the burner, comprising a hollow tube and a squared rod arranged longitudinally thereof, forming a plurality of ducts leading to the burner.
- 15 7. A heater comprising a burner provided with an annular oil groove, a well in communication therewith, a hollow oil chamber 20 arranged adjacent the burner, a hollow tube
- arranged between the oil chamber and oil well, being provided with a squared movable rod forming a plurality of ducts leading to the well, a valve arranged in said oil chamber, a reservoir for the liquid, and an automatic controlling means arranged between the oil chamber and reservoir for regulating the supply of fuel to the burner.
- 25 8. A heater comprising a burner adapted to burn a liquid fuel, a reservoir for the liquid, means interposed between the burner and the reservoir for restricting the flow of the fuel to the burner including a hollow tube and an angular rod extending longitudinally therein and forming a plurality of straight unobstructed ducts leading to said burner.
- 30 9. A heater comprising a burner adapted to burn a liquid fuel, a reservoir, a hollow nipple extending from the upper compartment to the lower compartment, a float arranged in the lower compartment, and a thermostatically controlled valve carried by said float adapted to close the opening in the nipple, when the oil has reached a predetermined level.
- 35 40 45 50 55 In testimony whereof I hereunto affix my signature.

HENRY M. SHEER.
